UNITED STATES PATENT OFFICE.

JOHN J. BENNETT, OF TAYLORSTOWN, PENNSYLVANIA.

HAT-PIN PROTECTOR.

SPECIFICATION forming part of Letters Patent No. 579,558, dated March 30, 1897.

Application filed September 22, 1896. Serial No. 606,643. (No model.)

To all whom it may concern:

Be it known that I, JOHN J. BENNETT, a citizen of the United States, residing at Taylors-
town, in the county of Washington and State
5 of Pennsylvania, have invented a new and
useful Hat-Pin, of which the following is a
specification.

This invention relates to hat-pins, and has
for its object to provide a simple and efficient
10 protector for covering and shielding the point
of the pin, said protector being capable of be-
ing easily and quickly attached or detached
from the point of the pin, and when attached
being securely locked upon the pin, so as to
15 avoid accidental displacement.

The invention consists in certain novel fea-
tures and details of construction, as herein-
after particularly described, illustrated in the
drawings, and embodied in the claims hereto
20 appended.

In the accompanying drawings, Figure 1 is
a perspective view showing a hat-pin and the
protector applied thereto. Fig. 2 is a detail
25 perspective view of the protector *per se*. Fig.
3 is a sectional view of the protector, showing
also the point of the pin in elevation.

Similar numerals of reference designate cor-
responding parts in the several figures of the
drawings.

30 The improved protector contemplated in the
present invention, while especially designed
for hat-pins, may be employed for shielding
the points of other pins and is in itself sus-
ceptible of changes in the form, proportion,
35 and minor details of construction which may
be resorted to without departing from the
spirit or sacrificing any of the advantages of
the invention.

Referring to the drawings, 1 designates a
40 pin which for the purpose of carrying out this
invention is provided near its pointed end
with an annular depression 2. The pin 1 may
have a head 3 of any preferred size or shape.

45 4 designates the improved protector, the
same comprising a tube or sleeve 5, which is
open at one end and closed at the other end
by means of a spring-strip 6. This spring-
strip is bent into circular form and secured
50 in any convenient manner at its central por-

tion to the tube or sleeve 5, being rigidly con-
nected thereto. The free ends of the strip 6
are overlapped just in front of the open end

of the sleeve 5, and each of said ends is pro-
vided with an opening 7, preferably of elip-
tical shape. Normally the free ends of the 55
strip 6 bear the relation to each other illus-
trated in Fig. 2, in which it will be seen that
the openings 7 are thrown out of alinement
with each other and with the open end of the
sleeve 5. 60

When it is desired to apply the protector to
the point of the pin, the thumb and forefin-
ger are pressed against the sides of the strip
6 until the openings 7 are brought into aline-
ment with each other and with the open end 65
of the sleeve 5. The protector is then passed
over the point of the pin and pushed thereon,
pressure being at the same time removed from
the strip 6, thus allowing the free ends of the
strip to move in opposite directions, where-
70 upon the ends of the openings 7 will bind in
the annular depressions 2 of the pin in the
manner shown in Figs. 1 and 3 and prevent
the protector from becoming accidentally dis-
placed from the point of the pin, while allow-
75 ing said protector to be forcibly withdrawn.
By making the depression 2 in the form of a
narrow groove with an abrupt shoulder to-
ward the point of the pin the protector may
not even be forcibly removed, but only by
80 pressing the strip 6 inward in the manner de-
scribed.

From the foregoing description it will be
seen that a very cheap, simple, and efficient
protector is provided and that the same may 85
be easily and quickly placed upon and re-
moved from the point of a pin, and that while
the protector is in place the pin-point is effect-
ively guarded and prevented from injuring
the person or clothing of the wearer. 90

Having thus described the invention, what
is claimed as new is—

1. A protector for the points of pins, con-
sisting of a spring-strip bent into substan-
tially circular form and having its ends over-
lapped and provided with openings for the
passage of the pointed end of the pin, the
ends normally tending to spring apart when
the pin is in the openings and thereby clamp
the protector on the pin, substantially as de- 95
scribed. 100

2. A protector for pin-points, consisting of
a spring-strip bent into substantially circular
form and having its free ends overlapped and

provided with openings, and a tube or sleeve attached to said strip and having its open end arranged in proximal relation to the free ends of the strip, substantially as described.

5 3. A protector for pins, consisting of a metal strip bent into substantially circular form and having its free ends overlapped and provided with openings, and a tube or sleeve secured rigidly to the central portion of said strip and having an open end adjacent to the free ends of the strip, the openings in the strip ends being normally out of alinement with each other and with the open end of the sleeve, substantially as described.

10 4. A hat-pin, provided near its point with

a depression, in combination with a protector consisting of a tube or sleeve adapted to slip over the point of the pin, and a spring-strip attached to said tube or sleeve and provided at its free end with an opening for the passage 20 of the pin, said strip being adapted to engage the depression in the pin and to interlock therewith, substantially as described.

In testimony that I claim the foregoing as my own I have hereto affixed my signature in 25 the presence of two witnesses.

JOHN J. BENNETT.
